US00D762112S

(12) **United States Design Patent**
Heidl et al.

(10) **Patent No.:** **US D762,112 S**
(b4) **Date of Patent:** **** Jul. 26, 2016**

(54) **PRODUCT PACKAGE**

- (71) Applicant: **National Concessions Group Inc.**,
Denver, CO (US)
- (72) Inventors: **Jeremy Heidl**, Denver, CO (US); **Gary Ross**, Fort Collins, CO (US); **Ralph Morgan**, Evergreen, CO (US); **Blake St. Clair**, Denver, CO (US); **Gentlechart Acres**, Denver, CO (US)
- (73) Assignee: **National Concessions Group Inc.**,
Denver, CO (US)
- (**) Term: **14 Years**

(21) Appl. No.: **29/508,198**(22) Filed: **Nov. 4, 2014**

(51) LOC (10) Cl. **09-03**
(52) U.S. Cl.

(Continued)*Primary Examiner* — Holly Baynham*Assistant Examiner* — Rhea Shields*(74) Attorney, Agent, or Firm* — Sheridan Ross P.C.(57) **CLAIM**

The ornamental design for product package, as shown and described.

DESCRIPTION

FIG. 1 is a front perspective view of the product package;
FIG. 2 is a top plan view thereof;
FIG. 3 is a front elevation view thereof;
FIG. 4 is a right elevation view thereof;
FIG. 5 is a left elevation view thereof;
FIG. 6 is a rear elevation view thereof; and,
FIG. 7 is a bottom plan view thereof.
The broken lines are included for the purpose of illustrating environment and form no part of the claimed design.

1 Claim, 3 Drawing Sheets(56)
